SYNCHRONISM CORRECTOR FOR TELE-
GRAPH SYSTEMS

Eugene R. Shenk, Brooklyn, N. Y., assignor to
Radio Corporation of America, a corporation of
Delaware

Application March 30, 1940, Serial No. 326,903

6 Claims. (Cl. 178—69.5)

This invention relates to improvements in a phase corrector for synchronizing the operating equipment at the receiving end of a telegraph system with the equipment at the transmitting end. The invention has particular application to the maintenance of a receiving distributor in phase synchronism with the speed of transmission of telegraph signals. The signals are caused to produce a corrective action whenever the speed of the receiving distributor departs from that of the transmitting distributor.

By a gradual process of evolution phase correctors have been developed and are now known in the art wherein the effects of distortion of the received signals are reduced to a minimum, and both front and back edges of the marking signal are utilized for phase correction. According to the teachings of Richard E. Mathes in his U. S. Patent No. 2,212,447, dated August 20, 1940, the times of occurrence of two, local circuit closures are compared, one with the front edge of a marking impulse and the other with the back edge of such a marking impulse. Two distinct time intervals were, therefore, derived, the durations of these intervals being differentiated from one another in such manner as to produce the necessary phase correction of a distributor.

The device disclosed in the instant application has for its object to improve upon the arrangements heretofore known. I have found that certain simplifications in the corrector circuit may be made, and that the operating characteristics of the phase corrector may be made more dependable under ordinary working conditions.

In my copending application Serial No. 326,902, filed on the same date of this application, I have disclosed another embodiment of a phase corrector for a telegraph system wherein the two aforesaid time intervals to be differentiated are derived in a somewhat different manner from that which is disclosed in this application. In the two embodiments illustrated, however, I have indicated certain similarities of circuit arrangements, particularly respecting the use of an electronic oscillator for producing a synchronized baud frequency output whereby any telegraph distributor may be maintained in synchronism with the incoming signals. In the respective cases, however, the oscillator is claimed only as an element in combination with other features by which the two disclosures are patentably distinguished.

It is an object of my invention to provide a dependable circuit arrangement for phase correction of a telegraph distributor, such as used in

10 multiplex telegraphy, and to provide means for measuring two time intervals, one of which elapses between the front edge of a marking signal and a local impulse produced in accordance with the receiving distributor phase and as near as possible to the normal center of a time allotment for reception of a dot unit impulse; and to compare this time interval with another time interval which immediately follows the first time interval and extends to the back edge of the marking signal.

15 It is another object of my invention to provide a phase correction system wherein use is made of a "pulse wheel" for derivation of a single train of local impulses, whose phase is to be maintained at the baud center of each marking impulse of dot unit length.

20 Other objects and advantages of my invention will be made apparent in the following detailed description wherein reference is made to the accompanying drawings, in which

25 Figure 1 shows diagrammatically a preferred circuit arrangement including the essential elements in combination for carrying out the invention; and

30 Figs. 2 to 7 inclusive are plots of electric impulses which occur in various parts of the circuit arrangement. These plots are all drawn to the same horizontal time scale in order to show the correlation of essential operations.

35 In the following description I have adopted a system of references to the several parts in combination as follows: All references bearing the initial V will be understood to represent discharge tubes either of the vacuum type or of the gas-filled ionization type. The gas-filled tubes are, however, conventionally shown in Fig. 1 by means of a black spot in the discharge zone. Resistors are referenced R₁, R₂, R₃, etc., while 40 capacitors are referenced C₁, C₂, C₃, etc. For the sake of brevity, the various tubes, resistors and capacitors will at times be mentioned by their identifying symbols alone.

45 In order that the requirements of the phase corrector circuit arrangement shown in Fig. 1 may be more readily understood, Figs. 2 to 7 are first referred to for explaining the steps of operation which are to be performed.

50 Fig. 2 shows a time plot of an incoming train of signals. The tone frequency signals are impressed across the transformer 2, during marking periods. Fig. 2 shows such a train of signals wherein the front edge of a marking element is in each case designated F, while the back edge thereof is designated B. Between B and F

the tone frequency is suppressed to represent a spacing period.

Referring to Fig. 3, I show the result of rectifying the keyed tone frequency signals. A curve of square wave formation is produced by rectification, the conductive times of the rectifier V1 being indicated by the wave crests, while non-conductive times are indicated by wave valleys.

Fig. 4 shows a plot of conductive and non-conductive times for tubes V2, V8, V17, V14 and V15. The marking signal commences at points marked M, at which moments a resulting voltage change across resistor R11 produces ionization of V4 and extinction of V6.

Fig. 5 shows a curve of impulse generation 15 locally by means of an impulse wheel having means for varying the magnetic flux across the poles of a pick-up coil. The impulse wheel will be understood to be mounted on the same shaft with the distributor whose phase is to be maintained in synchronism with the incoming signals.

Fig. 6 shows times of charging a condenser C12 as controlled by ignition periods of a gaseous discharge tube V4 and an extinction period of a second gaseous discharge tube V6, which is disposed in back-to-back relationship with the first tube. The condenser charge serves the purpose of measuring the front half of a marking signal of dot unit length.

Fig. 7 shows times of charging a condenser 30 C13, while V11 is blocked and from a reference voltage as established when V13 strikes in response to an A-pulse. The charge on C13 is used for measuring time intervals representing normally the trailing half of a marking signal of dot 35 unit length. As will be hereinafter explained in more detail, the times measured in accordance with the charging slopes on the curve of Fig. 6 are compared with those as measured in accordance with the effective charging slopes on 40 the curve of Fig. 7. A differentiating device is caused to produce phase correction in accordance with this comparison.

Referring now to Fig. 1, I show therein a transformer 2 the primary of which is connected to any suitable receiving apparatus, whereby the tone frequency signals may be delivered. The terminals of the secondary of the transformer 2 are connected to the anodes of a double-diode rectifier V1, while a center tap from the transformer secondary is connected across a resistor R11 to the grounded cathode of V1. A capacitor C4 is used to absorb the ripple component of the rectified wave energy. When V1 rectifies the signaling energy as during a marking impulse, V2, which normally operates at zero grid bias, is blocked by the signal and remains blocked for the duration of each marking element. A signal threshold is established by a normally slightly positive bias on V2 produced by means of resistors R25, R12, R13 and R14, which in combination constitute a voltage divider between the negative terminal of a suitable C source (not shown) and the positive terminal +B of a main anode potential source (not shown). R14 is made adjustable to a value which will suppress the effects of noise below that signal threshold.

The anode of V2 is coupled across C6 to a grid resistor R8 connecting with the control grid of a gaseous discharge tube V4. This grid is normally held at a negative bias from the -C source terminal, being connected thereto through R16 and R8.

Another gaseous tube V12 has its control grid connected through R21 to a terminal of C6 so as 75

to be controlled in the same manner as V4 is controlled, by an impulse across R16. Although V4 and V12 may be ionized at the same instant, it will be shown that V4 continues to discharge while V12 is almost immediately extinguished.

The anodes of V4 and V6 are intercoupled by C7, in order that when one of these tubes strikes, the other will have its anode potential reduced to a sufficiently low value to produce extinction of the previously maintained discharge therein.

V10 is a diode rectifier the anode of which is connected through R20 and R19 to the +B source terminal. The cathode of V10 is connected through a resistor R22 to the anode of V12 and is also directly connected to a terminal of C12. C12 is a capacitor which is used to store a charge, the voltage of which rises substantially in proportion to the duration of the front end timing interval, that is, during the first half of a received marking impulse of dot unit length. This will be explained hereinafter when the operation of the circuit is discussed. The second time interval to be measured starts at the center of a marking impulse of dot unit length and terminates with the back edge of the marking signal. If, however, the marking signal is of some multiple of a baud length, it is necessary to nullify the effects of false starts so that the final half baud interval within the duration of a marking impulse shall be the one to be compared with the front end time interval. The baud center as determined by the phase of the receiving distributor is coincident with the passage of teeth on the phonic wheel 6 in front of the magnetic pole faces of the pick-up coil 4. This relationship between the teeth of 6 and the pole faces of 4 is shown in the drawings. The magnetic reluctance at this point is less than at other positions of the phonic wheel 6. Consequently a surge impulse is developed in the pick-up coil 4 which produces a voltage drop in R3 leading to ground and to the cathode of V9.

The pick-up coil 4 is directly connected to the grid of V9 and biases this tube to cut-off. V9, as will be seen, is self-biased and normally draws current, its anode being connected to the +B source through R2. However, the anode of V9 is directly connected to the anode of V8, the grid of the latter being normally maintained at a zero bias so that this tube draws current until the commencement of a marking impulse.

When rectification of the marking impulse starts in V1 a potential drop occurs across R11 additional to that which is normally produced over the series circuit R14, R13, R12 and R11 between the +B terminal and ground. Grid 8 in V8 is, therefore, biased to cut-off by the marking signal, and the plate voltage of V9 is no longer influenced by the presence of V8. This causes V9 to amplify the impulse from the pick-up coil 4. This impulse is designated an A-pulse and is developed across C2 and R4, thus influencing the grid bias on gaseous discharge tubes V6 and V13, whose grids are connected to parallel resistive branches R6 and R18 of the A-pulse control circuit.

V17 has its grid connected in parallel with the grid of V2 and is, therefore, under the same control as V2 with respect to the rectified marking signal energy. That is to say, V17 is biased to cut-off during the reception of a marking signal. The purpose of V17 is to control the integration period from the baud center of a marking period to the back edge thereof, as measured by the storage of a charge on C13.

At the commencement of the back end integration period pick-up coil 4 delivers an A-pulse which is amplified and impressed positively across C2, and thence across R4 and R6 so as to cause V13 to strike. When V13 becomes ionized a discharge path for C13 is obtained through this tube and R7 so as to reduce the voltage on C13 to a reference level. This operation lasts for a negligibly small time interval and then V13 becomes automatically extinguished. Immediately thereafter C13 begins to charge again through R5, R9 and the diode rectifier V11 and continues to do so until V17 is again rendered conductive by the cessation of signal rectification in V1.

If the marking element of the signal endures for longer than one baud length, then a subsequent impulse or impulses will be delivered by the pick-up coil 4, thus causing V13 to repeatedly strike and to discharge C13 to the same reference level at which the useful charging period is to commence.

It will be noted that the A-pulse as applied to the grids of V6 and V13 serves both to terminate the front end integration period and to initiate the back end integration period. When V6 ionizes, the flow of current through R27 and V10 ceases because the charge already stored on C12 renders the cathode of V10 more positive than the anode thereof. Hence the charge stored on C12 remains until released by the momentary ionization of V12 at the front edge of the next marking impulse.

Since charges are stored repeatedly on C13 commencing with each successive momentary ionization of V13, provided V17 is blocked by a marking signal, it will be seen that only the last charge on C13 prior to the termination of a marking signal is rendered effective. This charge continues, therefore, for the duration of the last half-baud time interval during a marking impulse of any length, that is, when +B potential is applied across R5, R9 and through V11 to C13. The cancellation of charges on C13 prior to the final charge within a prolonged marking period is shown by the back edges U of certain voltage peaks indicated in Fig. 7.

Differentiation between the charges on C12 and C13 respectively is manifested by means of two triode tubes V14 and V15.

A connection is provided from the mid-tap on the secondary of transformer 2 to a potentiometer R25 and thence through resistors R24 and R26 to the grids of tubes V14 and V15 respectively. The potentiometer R25 has one terminal connected to the -C potential source and its tap is adjustable to render the grids of V14 and V15 more or less negative, as required, with respect to their cathodes. When V1 rectifies the marking signal voltage, however, the increased potential drop across R11 biases the grids of V14 and V15 below cut-off, so that these tubes cannot conduct during a marking signal. During a spacing signal the grid potentials on V14 and V15 are respectively influenced by the charges on C12 and C13, since C12 produces a potential drop across R23 and R24 which is greater or less than the potential drop produced by C13 across R26 and R27. It will thus be seen that during spacing intervals the charges stored on C12 and C13 in combination with the normal negative bias potential applied to the grids of V14 and V15 through R24 and R26, result in a control of

current flow in V14 and V15 proportional to the condenser charges.

The tubes V14 and V15 are arranged in a differential circuit relationship, their anodes being interconnected through a resistive circuit at the center of which direct current from a +B source is applied. This resistive circuit includes R38, R39 and R40 between the +B source and the anode of V14; it also includes R41, R42 and R43 in the anode circuit of V15. The relative conductivity across these two anode circuit paths determines the DC bias potential as applied to the grid of V3 with respect to its cathode. This is true because R40 and R43 constitute bias resistors in the input circuit of V3, and a grid biasing source 51 is inserted in series between the grid and cathode. This tube is provided with an independent anode potential source 50, the anode circuit including a choke L.

When the phase of the receiving distributor lags with respect to the incoming signals, the time interval measured between M and A, as indicated by the charge on C12, causes V14 to conduct at a higher rate than V15. This renders the bias on V3 more negative than normally. The effective resistance of V3, therefore, increases and produces a change in the effectiveness of C16 and C17 on the tank circuit 22. This is true because C16 and C17 in series with the anode resistance of V3 constitute a variable shunt path across the tank circuit 22. This tank circuit is constituted as part of the frequency control circuit for an oscillator V5. The frequency of V5 is increased by this action upon the tank circuit 22, thus speeding up the oscillator and correcting the phase of receiving distributor.

Because V5 is self-biased there will be no bias when the circuit is first turned on. Therefore, a pulse of plate current will flow in V23. This pulse is fed to V16 which amplifies and limits its amplitude as well as introducing a phase shift of substantially 180°. This amplified, inverted pulse is fed back to the tank 22, in which an oscillatory current is set up. Therefore, a voltage of substantially sine wave formation appears across the tank. This voltage initiates another change of current in V5 and the cycle is repeated.

The oscillator V5 has a grid-to-cathode circuit which includes potentiometer 54 and resistor 55. C18 is in shunt with resistor 55. Amplifier tube V7 has its cathode connected to the cathode of V5. V7 possesses a control grid circuit which includes a tap on potentiometer 54. V7 is, therefore, controlled in phase with V5, and its output power may be adjusted to any desired value by means of the adjustable tap on potentiometer 54. The output circuit of V7 includes the primary of a transformer 56 and an anode potential source 52. The secondary of transformer 56 delivers a controlled output frequency which is suitable for distributor phase correction purposes. The details of such a utilization circuit are not herein shown, since they form no part of the present invention. Reference is made, however, to U. S. Patent No. 1,747,248, granted February 18, 1930, to W. A. Knoop for disclosure of means controlled by an oscillator for adjusting the phase of a distributor to synchronization with the incoming signals.

I claim:

1. A system for synchronizing a telegraph distributor with a train of incoming signals comprising means for producing a first control condition coextensive with the period between the front

and back edges of a marking signal, means for producing a second control condition coextensive in time with a subsequent spacing signal, means for producing a periodic local impulse at the instant when the rotative element of said distributor crosses a reference meridian designated as the "baud center," means operative during said first control condition for storing a capacitive charge commensurate with the time interval from the front edge of a marking signal to the next succeeding local impulse, means for storing a second capacitive charge commensurate with the time interval commencing with a local impulse next preceding the back edge of a marking signal and ending with the arrival of said back edge, means operative during said second control condition for comparing the first and second capacitive charges, an oscillator having a phase correcting function, and means for varying the frequency of said oscillator in dependence upon the operation of said comparing means.

2. In a system for synchronizing a telegraph distributor with a train of incoming signals the marking elements of which are of baud length and multiples thereof, means including two capacitors for accumulating comparable charges, periodic pulse generating means controlled by said distributor for denoting the baud center with respect to which said distributor is phased, means operative only during the reception of marking signals for amplifying said periodic pulses, means for causing one of said capacitors to accumulate a charge commencing at the front edge of a marking signal, to cease charging in response to the next ensuing periodic pulse, and to store said charge until the arrival of the front edge of a next subsequent marking signal, means for causing the other of said capacitors to repeatedly accumulate charges starting from a reference voltage in response to each amplified pulse, to cease charging on arrival of the back edge of a marking signal and to store said charge through the period of a subsequent spacing signal, an oscillator for controlling the phase of said distributor, and means operative during the period of said spacing signal for controlling the frequency of said oscillator in dependence upon the relative voltages of the two charges thus capacitively stored.

3. In a synchronizing system, cyclically operable receiving apparatus including an oscillator the frequency of which is to be maintained in phase agreement with the reception of incoming

signals of baud length and multiples thereof, means for generating periodic timing impulses having a substantially constant phase relation to the operation of said oscillator, a frequency control circuit arrangement coupled to said oscillator, a pair of interval timing devices included in said control circuit arrangement, one of said timing devices being operative to measure an interval which starts at the front edge of a marking signal and ends at the first baud center within said marking signal, the other of said timing devices being operative to measure an interval which starts at a baud center next preceding the back edge of said marking signal and ends at said back edge, each of said baud centers being determined by said means for generating periodic timing impulses, and means in said frequency control circuit arrangement for differentiating between the time intervals measured by the two timing devices respectively, the last said means being operative only during the reception of spacing signals.

4. In a system for synchronizing an oscillator with a series of incoming signals whose baud-unit lengths are commensurate with half cycles of said oscillator, means including two capacitors for storing comparable corrective charges, said capacitors having means connected thereto for respectively integrating a front-end period and a back-end period of each marking signal, the two said periods combined being equal to a baud, means operable during reception of a spacing signal for differentiating between said corrective charges, and means responsive to the differentiating means for varying the frequency of said oscillator, thereby to maintain the desired synchronism with the incoming signals.

5. A system in accordance with claim 4 and including means effective upon that one of said capacitors which integrates the back-end period for repeatedly discharging the same to a reference voltage until a baud center is reached which next precedes the back edge of the marking signal.

6. A system in accordance with claim 4 and including means effective upon said capacitors for usefully storing thereon until the receipt of a spacing signal only such charges as are representative of the first-half baud and last half-baud respectively of each marking signal, means being provided for dissipating other charges on one of said capacitors which are accumulated during prolonged marking periods.

EUGENE R. SHENK.
